BOBBIN HOLDER

Harry V. Reynolds, West Los Angeles, Calif., assignor to Reynolds Industries Incorporated, Culver City, Calif., a corporation of California

Application August 21, 1948, Serial No. 148,235

Term of patent 7 years

(Cl. D58—13)

To all whom it may concern:

Be it known that I, Harry V. Reynolds, a citizen of the United States of America, residing in the city of Los Angeles, in the county of Los Angeles, State of California, have invented a new, original, and ornamental Design for a Bobbin Holder, of which the following is a specification, reference being had to the accompanying drawing, forming a part thereof.

Fig. 1 is a top perspective view of a bobbin holder showing my new design as it appears with the drawer pulled out partially and the cover in separated position:

Fig. 2 is an end elevational view of the same;

Fig. 3 is a top plan view of the holder; and

Fig. 4 is a side elevational view thereof, showing the side not seen in Fig. 1.

The bottom and opposite end of the box are conventionally plain.

I claim:

The ornamental design for a bobbin holder, substantially as shown and described.

HARRY V. REYNOLDS.
